UNITED STATES PATENT OFFICE.

JOSIAH M. WELBOURN, OF EDISON, OHIO.

GRAIN-SEPARATOR.

SPECIFICATION forming part of Letters Patent No. 281,589, dated July 17, 1883.

Application filed May 4, 1883. (No model.)

To all whom it may concern:

Be it known that I, JOSIAH M. WELBOURN, of Edison, in the county of Morrow and State of Ohio, have invented certain new and useful Improvements in Grain-Separators; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a portion of a separator-shoe provided with my improvement. Fig. 2 is a top view of the same. Fig. 3 is a bottom view of the same. Fig. 4 is a longitudinal vertical section of the same, and Fig. 5 is a cross-section of the same.

Similar letters of reference indicate corresponding parts in all the figures.

My invention has relation to improvements in separator-shoes; and it consists in the improved construction and combination of parts of the board in the bottom of a separator-shoe, through which the screenings and the seed are removed, as hereinafter more fully shown and described, and particularly pointed out in the claim.

In the separator-shoes generally used the board covering the opening in the bottom of the shoe, through which the screenings and the wild seed are removed, has been simply made to fit inside the edges of the opening, and been held in place by turn-buttons; but by this construction there has been the drawback and trouble, that in dry weather the board would shrink up and allow the grain to be spilled, and in damp weather the board would swell out, so that it could hardly be removed, and if once removed could not be pressed in place again, which has been the source of great loss of time and grain. To avoid these troubles I construct the opening and the board in the following manner:

In the accompanying drawings, A indicates

the bottom of the separator-shoe, and B the opening, which is provided upon the under side with a frame, C, the inner edges of which extend slightly inside the inner edges of the opening.

Covering the opening and resting upon the upper side of the projecting edges of the frame is a board, D, slightly smaller than the opening, which is provided with three, or more or less, downward-projecting screws, E, the heads of which are secured by transverse strips F, of metal, upon the upper surface of the bottom of the shoe, and the lower screw-threaded ends of which screws are provided with perforated yokes G, of metal, which rest with their ends upon the under side of the frame, and may be brought to bear against the same by thumb-nuts H, which fit and turn upon the ends of the screws.

In this manner it will be seen that the board may be made small enough to fit easily into the opening at all times, and will still cover the opening so that it will not leak, even if it should shrink considerably, and that the board may be removed with very little trouble and in a moment of time.

Having thus described my invention, I claim and desire to secure by Letters Patent of the United States—

As an improvement in separator-shoes, the combination of the bottom of the shoe having the transverse opening, the frame upon the under side, the board smaller than the opening, the screws having the transverse strips securing their heads, the perforated yokes so spanning the opening, and the thumb-nuts, as and for the purpose shown and set forth.

In testimony that I claim the foregoing as my own I have hereunto affixed my signature in presence of two witnesses.

JOSIAH M. WELBOURN.
